UNITED STATES PATENT OFFICE

2,380,637

ELECTRIC LANTERN

Elmer E. Drumm, Manitowoc, WIs.

Application May 27, 1943, Serial No. 488,642

5 Claims. (Cl. 240—10.63)

The present invention relates to improvements in electrical lanterns, and while the same has varied uses, it is particularly designed for trainmen, who demand a signal lantern having a plurality of exposed light bulbs that may be selectively illuminated in the event of failure of one of the bulbs.

The invention has primarily for its object to provide a lantern embodying the foregoing characteristics, in which a simple, efficient, and selective circuit closing mechanism is provided for easy manipulation, and inexpensive assembly.

Incidental to the foregoing, particularly in a lantern designed to provide different light reflection in selectively illuminating a pair of bulbs, a more specific object of the invention resides in the provision of a circuit closing mechanism, which permits not only maximum spacing between the bulbs, but also unequal spacing with reference to the axis of the reflector, a portion of which presents a concave reflecting surface for one of the light bulbs.

Another object is to provide a pair of spaced bulb sockets with laterally extending contact arms having their ends alined for selective engagement by a manually shiftable circuit closer.

Still further objects reside in insulating the sockets and contact arms from the casing, and extending the arms toward the periphery of the casing to aline their ends in different planes for selective engagement by a shiftable circuit closing mechanism mounted upon the peripheral wall of the casing and grounded thereto.

With the above and other objects in view, which will appear as the description proceeds, the invention resides in the novel construction, combination, and arrangement of parts, substantially as hereinafter described, and more particularly defined by the appended claims, it being understood that such changes in the precise embodiment of the herein disclosed invention may be made as come within the scope of the claims.

In the accompanying drawing is illustrated one complete example of the physical embodiment of the present invention constructed according to the best mode so far devised for the practical application of the principles thereof.

In the drawing:

Figure 1 is an elevation of a lantern incorporating the present invention;

Figure 2 is a fragmentary longitudinal section taken on the line 2—2 of Figure 4;

Figure 3 is a similar section taken on the line 3—3 of Figure 4.

Figure 4 is a transverse section taken on the line 4—4 of Figure 2; and

Figure 5 is a detailed section through the circuit closing mechanism taken on the line 5—5 of Figure 2.

Referring now more particularly to the accompanying drawing, the lantern generally indicated by the numeral 1, includes a casing 2, consisting of a cylindrical shell 3 for reception of a dry cell battery B indicated in dotted lines in Figure 2, and provided with spring terminals b and b'. The top of the shell 3, which is open for insertion of the battery B is provided with a detachable cover 4, while the casing has pivotally secured thereto a bail or handle 5. The lower end of the casing is provided with a guard ring 6, which also forms a support or base for the casing when desired. The ring 6 is attached to the casing by spaced legs 7 welded or otherwise secured to the periphery of the casing adjacent its lower end.

As best shown in Figures 2 and 3, the lower end 20 of the shell 3 is closed by a bottom wall 8, having a bridge piece 9 secured to its lower face by studs 10. A pair of insulating washers 11 positioned upon opposite sides of the bottom wall and interposed between the bridge piece 9 and the wall 25 serve to insulate the bridge piece from the shell.

Here it might be explained that the yieldable battery terminal b contacts the studs or rivets 10 to provide an electrical connection between the battery and bridge piece, while the other terminal b' engages the bottom of the shell to ground the battery to the same.

Mounted upon the lower end of the shell 3 is a reflector cup 12, the skirt 13 of which extends over the shell. The cup is secured to the shell 35 by bolts 15, or any other suitable connecting means, and to provide a tight seal between the shell and cup, the upper end of the skirt 13 is offset at 13' to receive a gasket g which abuts an external annular bead 14 formed on the exterior of the shell 3. Spaced screws 40 passing through the bottom of the cup 12 and the bottom 8 of the shell serve to compress the gasket g between the upper end of the cup and bead 14, the lower end of the shell being slotted at 15' to permit vertical movement of the attaching bolts 15.

The bottom of the cup 12 forms a reflecting surface and is provided with a circular concave depression 16, radially offset from the axis of the cup, and affording a reflector for the light bulb carried by the socket 17 secured to the cup within the depression 16. The socket 17 is insulated from the cup by washers 18 disposed upon opposite sides of the bottom of the cup. Fastened in like manner to the flat portion of the bottom of

the cup 12, and spaced a greater distance from the axis of the cup than the socket 17, is a second socket 18, insulated from the cup by washers 19.

As best shown in Figure 3, it will be noted that one end of the bridge piece 9 is offset to provide a resilient arm 20 for engagement with the light bulb carried by the socket 19, while the opposite end of the bridge piece is folded back upon itself to provide a resilient arm 20' engaging the lamp carried by the socket 17, thus forming an electrical connection from the battery B to the central terminals of both lamps.

Secured to each of the sockets 17 and 19 and insulated from the reflector cup 12, is a contact 21, which extends laterally from the sockets in different planes and at angles to each other to terminate in a common vertical plane adjacent to periphery of the cup.

In order to complete the battery circuit through the lamp sockets to the casing, a manually operable circuit closing mechanism 23 is provided, which comprises a contact arm 24 extending through an opening 25 in the bottom wall of the shell 3, and terminating in a laterally projecting finger 26, normally disposed between the aligned ends of the contacts 21, and spaced from the same. It will be apparent that as the contact arm 24 is longitudinally shifted from its normal position shown, it will engage one of the contacts 21 to ground the same to the casing, the arm 24 being in contact with the casing as best shown in Figure 1, thus selectively illuminating the light bulbs.

A crimped offset 26' formed in the arm 24 normally extends into the annular recess formed by the bead 14, to releasably latch the arm in its open position, while the spring tension created between the arm 24 and the shell when the crimp is moved out of the annular depression, serves to frictionally hold the arm in either of its circuit closing positions. For mounting the arm 24, a spacer channel plate 27 straddles the arm and engages the inner face of the shell 3 to prevent excessive bind between the arm and shell upon reciprocation of the former. The plate 27 carries a headed stud 28, which passes through the arm 24 and a longitudinal slot 29 formed in the shell 3, while a retainer plate 30 is mounted on the stud exteriorly of the shell for reciprocation in a longitudinal recess 31 formed in the shell.

A knurled nut 32 threaded upon the outer end of the stud 28 locks the assembly together and is held on the stud against accidental detachment by the upset end 33 of the stud. In operation the nut 32 serves as a manipulating button while the flat plate 30, operating within the longitudinal recess 31, limits reciprocal movement of the contact arm 24 in both directions.

From the foregoing explanation, taken in connection with the accompanying drawing, it will be apparent that a simple, inexpensive, and efficient lantern has been devised, which not only provides for selective, quick illumination of a pair of two exposed light bulbs mounted upon the end reflector, but also permits arbitrary selection of two forms of light rays, namely a diffused light and a more concentrated beam, the flat portion of the reflector serving to diffuse the light, while the concave portion concentrates the same.

Particular attention is directed to the novel circuit closing mechanism including the laterally extending contacts carried by the sockets and aligned for selective engagement by the shiftable contact arm. This construction is highly advantageous in that it permits the lamp sockets to be

spaced an unequal distance from the axis of the reflector, whereby one of the sockets can be positioned on the flat portion of the reflector, closely adjacent its periphery, thus allowing a concave reflector surface of a maximum diameter for the other lamp.

Further insulation of the lamp sockets from the casing, and grounding circuit closing mechanism to the casing, permits a materially simplified structure as compared with lanterns in which the circuit closing mechanism is insulated from the shell.

Attention is also directed to the ease of assembling the lantern, resulting from the fact that the shell and reflector cup and their mechanism, are separately completed, after which it is merely necessary to position the reflector cup upon the end of the shell, with the ends of the contacts 21 out of vertical alignment with the finger 26, and then rotate the cup to bring the spaced ends of the contacts into alignment with the finger, it being understood that the finger is in a neutral position to prevent obstructing rotary movement of the contacts with the reflector cup, which, when in proper position is secured to the shell by the screws 15.

I claim:

1. In an electric lantern comprising, a casing provided at one end with a flat reflector having a concave reflector surface formed in a portion of its face, a light bulb socket mounted upon both the flat and concave portions of the reflector and unequally spaced from the axis of the reflector, said sockets being insulated from the reflector, contact fingers connected to said sockets and extending laterally to a point adjacent the periphery of said casing and having their ends in vertical alignment, and a circuit closer vertically shiftable mounted upon the periphery of said casing and extending between the aligned ends of said contact fingers for selective engagement with said contact fingers, said circuit closer being grounded to said casing.

2. In an electric lantern comprising, a casing provided at one end with a flat reflector having a concave reflector surface formed in a portion of its face, a light bulb socket mounted upon both the flat and concave portions of the reflector and unequally spaced from the axis of the same, said sockets being insulated from said reflector, contact fingers secured to said sockets and extending laterally toward the periphery of said casing at an angle to each other and in different horizontal planes, the ends of said contacts being in the same vertical plane, and a vertically shiftable circuit closer mounted on said casing and extending between the ends of said contacts for selective engagement with the same, said circuit closer being grounded to said casing.

3. In an electric lantern comprising a casing provided at one end with a flat reflector having a concave reflector surface formed in a portion of its face, a light bulb socket mounted upon both the flat and concave portions of the reflector and unequally spaced from the axis of the same, a bridge piece carried by said casing for contact with the lamps carried by said sockets, contact fingers connected to said sockets and extending laterally toward the periphery of said casing and having their ends in vertical alignment, and a vertically shiftable circuit closer mounted upon said casing and extending between the aligned ends of said contact fingers for selective engagement with said contact members.

4. In an electric lantern comprising a casing

provided at one end with a flat reflector having a concave reflector surface formed in a portion of its face, a light bulb socket mounted upon both the flat and concave portions of the reflector and unequally spaced from the axis of the same, said sockets being insulated from said reflector, a bridge piece carried by said casing for contact with bulbs positioned in said sockets, contact fingers secured to said sockets and extending laterally towards the periphery of said casing in different horizontal planes and at angles to each other to vertically align the ends of said contacts, and a shiftable circuit closer mounted on said casing and extending between the ends of said contacts for selective engagement with the same, said circuit closer being grounded to said casing.

5. In an electric lantern comprising, a casing closed at one end, a cup secured to the closed end

of the casing and provided with a flat reflector wall having a concave reflecting surface formed in a portion of its face, a light bulb socket mounted upon both the flat and concave portions of the reflector and unequally spaced from the axis of the same, said sockets being insulated from said reflector, a bridge piece secured to and insulated from the bottom of said casing for contact with light bulbs carried by said sockets, contact fingers secured to said sockets upon the inner side of said reflector wall and extending toward the periphery of said cup with their ends in vertical alignment, and a shiftable circuit closer mounted upon the interior of said casing and projecting through the end wall and extending between the aligned ends of said contacts for selective engagement with said contact fingers.
